ATTORNEY.

UNITED STATES PATENT OFFICE.

MARK REUBIN, OF BROOKLYN, NEW YORK.

CROSS-WORD-PUZZLE GAME.

Application filed April 15, 1925. Serial No. 23,384.

To all whom it may concern:

Be it known that I, MARK REUBIN, a citizen of the United States, residing at Brooklyn, in the county of Kings and State of New York, have invented certain new and useful Improvements in Cross-Word-Puzzle Games, of which the following is a specification.

This invention relates to cross word puzzle games and more particularly to a novel and fascinating checker-board game which may be played according to various sets of rules and which game embodies the element of uncertainty, yet permitting both election and arrangement of playing objects on the playing surface of the board.

One of the objects of my invention is to provide a game involving a number of uncertainties which are determined by the playing objects when considered in relation to set rules and designated spaces on a checker-board surface so that the game may be won or lost by one of two players when certain combinations are completed on the checker-board surface which correspond to certain markings on the playing objects.

In order to more fully understand and appreciate my invention, reference is had to the accompanying drawings, wherein;

Figure 1 is a view of the checker-board surface showing the arrangement of the objects and the designations on said surface.

Figure 2 designates one face of one of the playing objects.

Figure 3 designates a different object used in playing the game.

Reference being had to the drawings, it will be observed that I provide two playing surfaces consisting of three rows 5, 6, 7, arranged similar to a checker-board. There are fifteen playing objects for each player which are arranged on the two bottom rows on each half of the board. In the lower, right hand corner 8 of each section or half of the playing board, is a recording playing surface in which there are fifteen blocks lettered and numbered according to markings on the fifteen playing objects used on the checker-board surfaces. In other words, on

one face of each playing object appears a letter or the designation of Ace, Ten, Queen, King and Jack which corresponds to designations of certain blocks in the recording playing surfaces. These five designations in the blocks also represent forfeits of all, zero, one, three and two respectively, it

being assumed that the game may be played for chips or for points, as the case may be so that when these five blocks are completed by a player, the rules provide that the game is won. In addition, the remaining ten designated blocks correspond to letters appearing on one face of the ten playing objects used on the checker-board playing surface.

In the lower left hand corner of the checker-board surface, may be printed the rules of the game or this portion of the board may be left blank and the rules printed on separate sheets for the instruction of the players. In addition to the fifteen playing objects, a number of additional objects are provided, which may be utilized as a king when one of the objects shall have advanced to the bottom row of the opposite player or the opponent.

When the objects are set on the playing surface as shown by Figure 1, the players commence the game, the same as in the usual game of checkers, advancing one object at a time. When the space is vacant and the objects are in contiguous blocks, the rule provides that one object must jump or replace the object of the opponent. In so replacing the object which has been jumped, the player, in lifting the displaced object, turns it up, so as to reveal the marking on the reverse face thereof, which marking will correspond to one of the fifteen lettered and designated blocks appearing in the lower right hand corner of the board. If one of the playing objects is a jack, queen, king, ten or ace, it will also represent a forfeit which one player must give to the other, assuming that both players start the game with the same number of chips, for instance.

It is of course understood that before the game is played, all of the objects are shuffled about indiscriminately and arranged so that their location is not known. When the objects are displaced by one player, and then positioned in the lettered and designated blocks of the lower right hand corner of the board, a combination may be completed. The object of the game, of course, is to complete the word "Won." However, as the game is played, the player may not be able to displace the objects having the designations "Won" thereon, consequently the player will be obliged to complete either the word "Tied" or the word "Lost." It

will thus be seen that one of the players will lose his own game due to the fact that he has displaced objects on which these letters appear, as above indicated. The five blocked surfaces containing the designations "Ace", "Ten", "Queen", "King" and "Jack" are provided to introduce a poker hand combination, which when completed, also wins the game as provided by the rules and 10 also a means of recording points, it being of course understood that the points lost by one player are the gain of the opposite player.

In actual practice, the objects of each 15 player are colored differently so that they may be distinguished one from the other. The shape of the objects, of course, is an arbitrary matter but for convenience, I have shown the objects as being circular, similar 20 to the ordinary checker. Under certain conditions, it will be seen that the letter "O" will complete the word "Won" and the word "Lost" at the same time when the blocks "W", "N", "L", "S", and "T" have been 25 arranged on the playing surface. In this event, of course, the game would result in a tie and would require being played over again. In playing the game, the players of course would be governed to some extent in 30 the matter of the choice between completing the word "Lost" and the word "Tied", assuming that the letter "T" must be placed in either of two blocks. Other than the above, the game constitutes a number of 35 uncertainties, requires very little or no skill, is very arbitrary and may be governed by a few simple rules whereby the game is instructive and entertaining to young and old alike.

40 While I have illustrated and described my invention with some degree of particularity, I realize that in practice various alterations therein may be made. I therefore reserve the right and privilege of 45 changing the form of the details of construction, or otherwise altering the arrangement of the correlated parts without departing from the spirit of the invention or the scope of the appended claims.

50 Having thus described my invention, what I claim as new and desire to secure by United States Letters Patent is:—

55 1. A game of the class described comprising a checker-board playing surface and a checker-board recording surface having a plurality of designated blocks and a set of playing objects, said playing objects having

designations on one face thereof corresponding to the designated blocks of the recording surface.

60 2. A game of the class described comprising a divided checker-board playing surface and contiguous checker-board recording surfaces having a plurality of designated blocks, a set of playing objects for each division of the playing surface, 65 said playing objects having designations on one face thereof corresponding in number and to the designated blocks of the recording surfaces.

70 3. A game of the class described comprising a divided checker-board playing surface and contiguous recording surfaces having horizontal and vertical lettered blocks, a set of playing objects for each division of the playing surfaces, each object having a blank face and a designation on the opposite face corresponding to the designations on the recording surfaces, the number of blocks in each recording area corresponding in number with each set of 75 playing objects.

80 4. A game of the class described comprising a divided checker-board playing surface and a contiguous checker board recording area consisting of a number of blank squares or blocks and lettered squares or blocks completing the words "Tied", "Lost" and "Won", a set of playing objects each having an individual letter corresponding to one of the letters of the said words, there being the same number of playing objects to each set as the number of lettered 85 squares or blocks in the recording area.

90 5. A game of the class described comprising a divided checker-board playing surface and a contiguous checker-board recording area consisting of a number of blank squares or blocks and lettered squares or blocks completing the words "Tied", "Lost" and "Won", certain of the squares or blocks of the recording area having playing card designations, a set of playing objects for each division of the board, each object having a designation thereon corresponding with either a letter of the same words or a playing card designation, said objects corresponding in number to the number of letters and playing card designations 95 in the recording area.

100 In testimony whereof I affix my signature.

MARK REUBIN. [L. s.]
